D 11,437

UNITED STATES PATENT OFFICE

CHARLES H. LEARNED, OF MERIDEN, CONNECTICUT.

DESIGN FOR COFFIN-SCREWS.

Specification forming part of Design No. **11,437**, dated September 30, 1879; application filed February 27, 1879.
[Term of patent 7 years.]

To all whom it may concern:

Be it known that I, CHARLES H. LEARNED, of Meriden, county of New Haven, State of Connecticut, United States, have invented a new Design for Coffin-Screws; and I do declare the following, when taken in connection with the accompanying illustration and letters of reference marked thereon, to be a full, clear, and exact description of the same.

Letter A is a side view of the lily-flower in *alto-rilievo*, which is represented as forming the head in part of the screw; letters D E, views of leaves in *alto-rilievo*, one on each side of the flower; letters B C, views of the lily-flower in *basso-rilievo*, one on each side of the plate; letters F G H I, views of leaves on each side of each flower on the plate; letters J K, views of other leaves.

The invention relates to a design for screws used in securing coffin-covers, commonly called "coffin-screws;" and the invention consists in the configuration and ornamentation, as hereinafter described, and as shown in the accompanying illustration.

The head of screw, as seen, (letters A D E,) is a representation of a lily-flower with leaves in *alto-rilievo*, the lily-flower, letter A, as open in bloom, and the leaves one each side, as seen, (letters D E.) The plate, of oblong shape, has represented on its surface, in *basso-rilievo*, on each end, a lily-flower, with leaves represented as belonging to each flower. The leaves are

represented on the plate as one each side of a flower, as seen, (letters F G H I.) There are represented two other leaves, letters J K, as being one under each flower.

The screw passes through the center of the plate, so that the base rests thereon.

The essential feature of the design I regard as the representation for thumb-screws of a lily-flower with leaves in *alto-rilievo* for the head, and the representation of a lily-flower with leaves in *basso-rilievo* for the plate, represented as on each end.

The screw may be used with a different plate, or the plate with a different screw, it only being essential that there be some plate used with the screw, or some screw used with the plate.

The design of the oblong plate is shown and claimed in another application, filed on the 28th of February, 1879.

I claim—

The design for coffin-screws, consisting of the representation, in *alto-rilievo*, for the head, of a lily-flower open in bloom, and with leaves, in *alto-rilievo*, represented as belonging to the flowers, as shown in the accompanying illustration.

CHAS. H. LEARNED.
